UNITED STATES PATENT OFFICE.

LLOYD B. HUBBARD, OF WICHITA FALLS, TEXAS.

OILING SYSTEM.

Application filed April 4, 1922. Serial No. 549,467.

To all whom it may concern:

Be it known that I, LLOYD B. HUBBARD, a citizen of the United States, residing at Wichita Falls, in the county of Wichita and State of Texas, have invented a new and useful Oiling System, of which the following is a specification.

This invention relates to automatic oiling systems for automobile and other combustion engines.

The object of the invention is to provide a vacuum operated oiling system of this character in which pumps and gears are eliminated and a perfect circulation of the oil insured.

Another object of the invention is to so construct an oiling apparatus of this character that the motor will be stopped before the supply of oil is exhausted, thus preventing the burning out of the bearings.

Another object is to provide such an apparatus operable to keep the oil and the motor cool, to filter out any gasoline which may leak around the piston rings into the crank case and return it to the engine for use as fuel.

Another object is to provide such an apparatus equipped with an emergency oil supply and with means to stop the motor when the reserve supply is exhausted.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

40 In the accompanying drawings:—

Figure 1 represents a central vertical section of the apparatus constituting this invention.

45 Fig. 2 is a horizontal section taken on the line 2—2 looking in the direction of the arrows *a*, and

Fig. 3 is a similar view taken on the same line looking in the direction of the arrows *b*.

50 This oiling system includes an apparatus in the form of a closed tank 1 having a vacuum chamber 2 encased thereby and which communicates therewith by means of an outlet 3 controlled by a check valve 4. An oil supply pipe 5 opens into the vacuum chamber 2 at the top thereof and a baffle

plate 6 is located in said chamber adjacent said pipe opening.

The pipe 5 is designed to extend into the crank casing (not shown) and is equipped with a two way valve 7 adapted to be actuated by any suitable means for bringing into communication with pipe 5 pipe 8 which extends into the crank chamber or pipe 9, the latter being longer than pipe 8 and designed as an emergency supply pipe for purposes presently to be described. A pipe 10 leads from the bottom of tank 1 and is designed to return the oil to the crank case to insure the proper circulation of the oil.

70 A pipe 11 leads from the upper end of the vacuum chamber 2 to the intake manifold of the engine (not shown) and has a reduced mouth 24 opening into said chamber.

A cap 12 has threaded engagement with a 75 boss or neck 14 carried by the top of chamber 2 and through which extends a valve stem 15 having mounted on its upper end a ball valve 16 which may be termed the atmospheric valve. The cap 12 is provided with a plurality of openings 13 which permit atmospheric air to be admitted to said cap and when the ball valve 16 is raised, the air passes down into the vacuum chamber 2 for cutting off the oil supply through pipe 5 in 80 a manner to be presently described. A float 17 is mounted in the chamber 2 on the valve stem and is operable for controlling the supply of oil admitted through pipe 5. A T-shaped valve 18 is also carried by the stem 90 15 and the shank or stem 19 thereof is loosely engaged with a guide rod 23 depending into the chamber 2 from the top thereof. The head 20 of the valve 18 is designed to close the elongated opening 24 which communicates with the vacuum pipe 11 when the oil in the chamber 2 reaches a predetermined height.

The valve 18 is shown mounted on the stem 15 between two spaced disks 21 and 22 as is shown clearly in Fig. 1. The stem 15 below the float 17 is equipped with a stop 25 which in its lowest position is yet above spider 26, through which the stem 15 extends and which serves as a guide for stem 15.

105 In the use of this apparatus the suction pipe 5 leads from the vacuum chamber 2 and extends into the crank case (not shown), the lower end 8 of said pipe being immersed in the oil a depth depending upon the depth of 110 oil carried by the crank case.

When the motor is started the suction in

the manifold exhausts the air in chamber 2 creating a suction in pipe 5 which operates to draw the oil up through this pipe into the vacuum chamber 2. The oil discharged 5 through pipe 5 strikes the baffle 6 which guides or directs the entering oil to the bottom of the chamber.

As the oil rises in tank 2 the float 17 rises with it and when the chamber is full this 10 float will engage the disk 21 and force the valve stem 15 upward opening the valve 16 permitting the air to enter chamber 2 and release the vacuum therein. At the same time that the valve 16 is opened the valve 18 15 closes the opening 24 leading to the vacuum pipe 11. The opening of valve 16 and closing of valve 18 operates to stop the flow of oil through pipe 5 and permits the oil to escape from chamber 2 into tank 1 through 20 the check valve 4, from whence it passes out through pipe 10 back to the crank case.

As the oil flows out of the chamber 2 the float 17 lowers until it engages the stop 25 on the valve stem 15 and thereby forces said 25 stem downward to the position shown in Fig. 1 closing the valve 16 and opening valve 18 thereby again establishing a vacuum in chamber 2 and causing the oil to flow through pipe 5 into chamber 2.

30 The emergency oil pipe 9 extends into the oil of the crank case a greater depth than the pipe extension 8 and may be used to restart the engine after it has stopped owing to lack of fuel supplied by pipe 8. This is 35 accomplished by turning the valve 7 to bring said pipe 9 into communication with pipe 5 and oil will be supplied until the reserve is exhausted.

From the above description it will be obvious that when the suction pipe 5 ceases to 40 draw oil, air will be sucked in therethrough and carried through the vacuum chamber 2 out through port 24 into the vacuum pipe 11 and to the manifold between the carburetor and the engine. This inflowing air will 45 render the material fed to the motor non-combustible since this supply of air will cause the flowing of gasoline to cease and therefore the motor will stop for lack of fuel. This stoppage of the motor when the 50 oil ceases to be supplied prevents any possibility of the bearings being burned out. Should it be desired to continue running the motor after the first stoppage thereof, the 55 valve 7 is turned to bring into communication the reserve oil supply pipe 9 and the operation above described will be repeated and the engine continue to run until the reserve is exhausted and the motor will 60 again stop as in the first instance.

More or less gasoline in liquid as well as vapor form enters the crank case through leakage around the piston rings. The liquid gas mixes with the oil in the crank case and

is sucked out into the tank 1, and being hot 65 the gasoline is vaporized and drawn into the intake manifold while the heavy oil passes to the bottom of the tank and is returned to the crank case. Thus is the gas filtered from the oil in tank 1 and added to the fuel supply in the intake manifold. The vaporized gas in the crank case is not filtered off until the supply of oil is exhausted and pipe 5 draws this vapor and air from the crank case into tank 1 from which it is drawn into the 70 intake manifold and when this mixture of gas and air becomes too lean to support combustion, the motor will stop for lack of fuel.

Since all lubricating oils when heated give off vapor capable of combustion, this 80 system supplies a suitable amount of fuel to the motor in addition to the gasoline vapors which are sucked from the tank 1 and fed to the motor through pipe 11.

This drawing off of the gasoline which 85 has leaked into the crank case leaves the lubricating oil much more serviceable as a lubricant.

Owing to the cooling effect produced the 90 lubrication will be more perfect, the lubricating miles increased, and the life of the motor prolonged.

To permit oil to flow out of tank 1, an air passage 27 opens through neck 14 and top 95 into the tank as is shown clearly in Fig. 1.

I claim:

In an apparatus of the class described, a closed tank having a vacuum chamber depending therein from the top thereof with a space between the side walls of said chamber and the tank, a check valve controlled outlet affording communication between the bottom of said chamber and said tank, an oil supply pipe opening into said vacuum chamber through the top thereof, a suction pipe leading from the upper end of said vacuum chamber, a neck carried by the top of said vacuum chamber with a bore extending therethrough, said neck and top having a bore connecting the interior of the tank with the atmosphere, a perforated cap mounted on said neck, a vertically movable float controlled stem on its outer end to normally close the bore leading to the chamber, another valve carried by said stem to close said suction pipe on the opening of the bore in the neck, a guide for said last mentioned valve depending from the top of said chamber, a float loosely mounted on said stem, and a stop on said stem to engage said guide. 105 110 115 120

In testimony that I claim the foregoing as my own, I have hereto affixed my signature in the presence of two witnesses.

LLOYD B. HUBBARD.
